UNITED STATES PATENT OFFICE

SOCRATES A. XIPPAS, OF BUFFALO, NEW YORK

DESIGN FOR A FRANKFURTER ROASTER

Application filed May 13, 1929. Serial No. 31,204. Term of patent 14 years.

To all whom it may concern:

Be it known that I, SOCRATES A. XIPPAS, a citizen of the United States, residing at Buffalo, in the county of Erie and State of New York, have invented a new, original, and ornamental Design for Frankfurter Roaster, of which the following is a specification, reference being had to the accompanying drawing, forming a part thereof.

The figure is a perspective view of a frankfurter roaster showing my new design.

I claim:

The ornamental design for a frankfurter roaster, as shown.

SOCRATES A. XIPPAS.
